DOOR FRAME FOR RAILWAY HOPPER CARS

William E. Wine, Parker, Va.

Application June 10, 1947, Serial No. 753,752

9 Claims. (Cl. 105—253)

1

My invention relates to railway hopper cars and more particularly to door frames for the hopper.

One of the principal objects of the invention is to provide a hopper door frame in which the flange thereof for cooperating with the hinged door is renewable.

Another object of the invention is to seal the upper portion of the hopper against the escape of lading where the door frame adjoins the car center sill.

A primary feature of the invention consists in providing the hopper door frame with portions surrounding all sides of the lading discharge opening of the hopper which are disposed in a common plane and in riveting to those portions an angular member which is formed with an outwardly projecting flange for cooperating with the hinged door of the hopper to seal the lading discharge opening thereof against the escape of lading.

Another feature of the invention consists in providing a door frame for the hopper of a railway car comprising a rolled member having portions adapted to be secured to the bottom and to the inner and outer sides of the hopper and an angular member having a flange riveted to the rolled member and also having an outwardly extending flange for cooperating with the hinged door of the hopper to seal the lading discharge opening thereof against the escape of lading.

Another feature of the invention consists in providing the upper portion of the inner side sheet of the hopper which inclines downwardly and outwardly to clear a flange at the lower edge of the center sill with offset means adjacent the door frame of the hopper to close the upper inner corner of the hopper.

Other and more specific features of the invention, residing in advantageous forms, combinations and relations of parts, will hereinafter appear and be pointed out in the claims.

In the drawings,

Figure 1 is a cross sectional view of one-half of a railway hopper car showing the discharge end of one of the hoppers in elevation.

Figure 2 is an outside side elevational view of the construction illustrated in Figure 1.

Figure 3 is an enlarged cross sectional view taken on line 3—3 of Figure 1.

Figures 4 and 5 are enlarged cross sectional views taken on lines 4—4 and 5—5 respectively of Figure 1.

Figure 6 is a sectional view taken on line 6—6 of Figure 3.

2

Figure 7 is a front elevational view of the hopper door frame.

Figure 8 is a side elevational view of Figure 7 when viewed in the direction indicated by the arrows 8—8.

Figure 9 is a front elevational view of the renewable door sealing flange unit of the door frame.

Figure 10 is a side elevational view as seen when looking in the direction of the arrows 10—10.

Figures 11 and 12 are enlarged sectional views taken on lines 11—11 and 12—12 respectively of Figure 9.

15 The conventional railway hopper car consists of a plurality of pairs of hoppers and the hoppers of each pair are disposed on opposite sides of the center of the car and are of identical construction. Only one of the hoppers on one side 20 of the car center is, therefore, illustrated in the drawings and will be described herein.

In the drawings, 1 indicates the car center sill which, in the embodiment of the invention here disclosed, consists of a single unitary member 25 having a top wall 2, a side wall 3 and a flange 4 which extends outwardly from adjacent the lower edge of the side wall 3. Overlying the center sill is a longitudinally extending ridge sheet 5 which on each side of the center of the car has 30 a downwardly inclined portion 6 to direct the lading within the car onto opposite sides of the center sill into the respective hoppers. Each inclined portion 6 preferably terminates in a substantially vertical flange 7 which is riveted to the 35 upper portion of the adjacent side wall of the center sill.

Extending longitudinally of the car parallel with the center sill at each side of the car is a side sill 8 which may be of conventional angular shape having a vertical flange 9 and a horizontal flange 10. Metal sheets 11 forming the side walls of the car may be advantageously secured at their lower edges to the vertical flange 9 of the adjacent side sill in overlapping relation to its outer face.

Instead of being formed of separate sheets, each hopper of the car may be formed of a single sheet which respectively has inner and outer side sheet portions 12 and 13 respectively and a floor 50 or bottom sheet portion 14 which inclines downwardly. The upper portion of the inner side sheet or portion of the hopper is riveted to the upper portion of the adjacent side wall of the center sill and inclines downwardly and outwardly, as indicated at 15, to clear the outwardly 55 of the side wall.

projecting flange 4 of the center sill. From adjacent this flange, the inner side sheet of the hopper extends downwardly in a substantially vertical plane.

The upper portion of the sheet forming the outer side of the hopper is riveted along its upper edge to the inner face of the vertical flange 9 of the side sill and from there inclines downwardly to clear the inner edge of the inwardly projecting horizontal flange of the side sill, from where it inclines downwardly and inwardly a sufficient amount that the appurtenances for keeping the hopper door closed will not project beyond the A. A. R. equipment limit line.

Extending transversely of the car between adjoining hoppers is a cross ridge sheet 16 which inclines downwardly and terminates adjacent the lading discharge opening of the hopper. Secured to the lower end of the cross ridge sheet, preferably by rivets, and extending from adjacent the center sill to an adjoining side sill is an angular member 17 which forms the upper portion of the door frame and to which a door 18 having inwardly extending marginal flanges 19 is pivotally connected. This member is generally of Z-shape in cross section having a web 20 and upper and lower flanges 21 and 22 respectively. The upper flange 21 is riveted to the cross ridge sheet 16 in lapping relation to the under face thereof, while the web 20 may conveniently be arranged to be disposed at substantially right angles to the flange. Positioned within the angle formed by the web 20 and the upper flange 22 of the member 17 are spaced hinge butts 23. Each hinge butt has base portions 24 and 25 respectively integrally connected by spaced lugs 26 which are formed with aligned apertures for receiving a pivot pin 27. The base member 24 of each hinge butt has portions 28 extending laterally from the hinge lugs by which the hinge butt is riveted to the upper flange 21 of the member 17. The base portion 25 which only extends between the hinge lugs is riveted to the adjacent portion of the web 20 of the member 17, the upper end of the rivet being preferably countersunk so as not to interfere with free pivotal movement of the door 18.

Hinge straps 18a of any suitable construction may be secured to the outer face of the door and be bent upwardly where at their ends they are suitably apertured to receive the hinge pins 27. As is conventional in hopper car construction, a door spreader 29 is secured to the outer face of the door and extends beneath the center sill for attachment to the door (not shown) of the adjacent hopper on the other side of the center sill so that the doors will swing in unison. In the present embodiment of the invention, the door spreader is of Z-shape and the web 30 thereof serves as convenient means to which extensions or door arms, one of which is shown in dot and dash lines in Figure 2, may be conveniently connected adjacent opposite ends thereof.

Bounding the sides and bottom of the hopper adjacent the lading discharge opening is a rolled member 31 which is generally of U-shape having a web portion 32 which underlies the floor sheet 14 of the hopper and upwardly extending legs 33 and 34 which are respectively secured to the inner and outer side walls of the hopper. The upper ends of the legs 33 and 34 are preferably welded to the outer ends of the upper member 17. In addition to having portions 35 for attachment to the adjacent walls of the hopper, each part of the U-shaped member has a flange 36,

which is disposed in a common plane substantially parallel with the lading discharge opening. The lower flange 22 of the angular member 17 is also disposed in the same common plane so that its outer face and the outer faces of the flange 36 of the rolled member afford means to which a door rim 37 may be conveniently attached. As the door rim is preferably substantially rectangular, a plate 38 whose outer face is disposed in the same common plane is welded along one side to the outer leg 34 of the U-shaped member and is welded along its upper edge to the lower edge of the adjacent portion of the flange 22 of the upper member. This plate which is of generally triangular shape changes the shape of the opening formed by uniting the upper member 17 and the rolled member 31 into a substantially rectangular opening so that the door rim 37 may be readily secured to all parts of the frame.

The door rim 37 is preferably of angle shape having a laterally extending flange 39 and an outwardly projecting flange 40 for cooperating, as clearly shown in Figures 4 and 5, with the inner faces of the marginal flanges 19 of the door to prevent the accidental escape of lading from the hopper. The lateral flange 39 of the door rim contacts with and is riveted, as indicated at 41, to all portions of the door frame including the substantially triangular plate 38. At its upper end the flange 36 of the inner member 33 of the rolled member is cut away, as indicated at 42, so as to clear the outwardly projecting flange 4 of the center sill. And the outer edge portion of the flange 36 of the outer leg 34 of the member 31 may be cut away slightly, as indicated at 43, to receive the hook 44 of the door lock supporting mechanism shown in dot and dash lines in Figure 2. Where it overlaps the cut away portion 43, the lateral flange 39 of the door rim 37 is similarly cut away. The consequent loss of rigidity in the rim member which would be caused by the cutting away of part of the lateral flange 39 at the upper right hand corner of the door rim is compensated for by providing the rim with a supplementary flange 45 which while disposed in the same plane as flange 39 extends inwardly of the flange 40. The door rim is somewhat similarly constructed at the lower left hand corner thereof, in that the lower corner of the flange 39 is preferably cut away so that the door opening may be of maximum size. Loss of strength of the door rim is also avoided at this point by providing a supplementary flange 46 which extends inwardly with respect to the flange 40 disposed in the same plane as the flange 39.

As the upper inner portion of the door frame terminates some distance from the adjacent side wall of the center sill, the inclined portion 15 of the inner hopper side sheet is bent upwardly and outwardly to form a substantially triangularly shaped portion 47 for closing that portion of the hopper. At its upper edge the triangular portion 47 may be welded, as indicated at 48, to the under side of the adjacent portion of the cross ridge sheet 16 and for its entire length the triangular portion may advantageously be disposed in a plane which is substantially parallel with the plane of the adjacent portion of the cross ridge sheet. As shown in Figure 6, the inner side sheet of the hopper continues downwardly substantially vertically for the outer edge of the triangular portion 47 so that it may be conven-

iently attached to the adjacent portion of the inner leg 33 of the door frame.

An angle member 49 may be advantageously employed to support the inner portion of the hopper door frame. This member may conveniently have an upper flange 50 which is overlappingly secured to the projecting flange 4 of the center sill and a main portion 51 which is connected directly to the adjacent portion of the door frame and to the inner side sheet as well.

In addition to other advantages, the present invention permits the door sealing flange 40 to be replaced by cutting away the rivets connecting the door rim 37 to the door frame. It, therefore, becomes unnecessary to replace the entire frame when only the door sealing flange needs to be replaced as a result of wear due to corrosive action which takes place principally around the lower portion of the door sealing flange.

Various modifications may be made in the embodiment of the invention here disclosed without departing from the scope of the invention as it appears in the appended claims.

What I claim is:

1. A door frame for the hopper of a railway car provided with a hingedly mounted door having inturned marginal flanges for closing the lading discharge opening of the hopper, said door frame comprising a rolled member having portions adapted to be respectively secured to the bottom and to the inner and outer sides of the hopper, an upper member welded to the upper ends of the portions of said rolled member which are adapted to be secured to the inner and outer sides of the hopper, each of said portions having flanges whose outer surfaces are disposed in a common plane, and an angular member having a flange riveted to said flanges and also having an outwardly extending flange for cooperating with the marginal flanges of the hinged door to seal the lading discharge opening against the escape of lading.

2. A door frame for the hopper of a railway car provided with a hingedly mounted door having inturned marginal flanges for closing the lading discharge opening of the hopper, said door frame comprising a substantially U-shaped member having a web portion adapted to be secured to the bottom of the hopper and leg portions adapted to be respectively secured to the inner and outer sides of the hopper, an upper member connecting the upper ends of said leg portions, each of said portions and said upper member having flanges whose outer faces are disposed in a common plane, and an angular member having a portion contacting said faces and riveted to said flanges, said angular member also having an outwardly extending flange for cooperating with the marginal flanges of the hinged door to seal the lading discharge opening against the escape of lading.

3. A door frame for the hopper of a railway car provided with a hingedly mounted door having inturned marginal flanges for closing the lading discharge opening of the hopper, said door frame comprising means secured to the hopper and bounding the lading discharge opening, said means having portions on four sides of said opening whose outer faces are disposed in a common plane, and an angular member having a flange riveted to each of said portions and also having an additional flange projecting outwardly therefrom for cooperating with the inner faces of said marginal flanges of the hinged door to seal the

lading discharge opening against the loss of lading.

4. A door frame for the hopper of a railway car provided with a hingedly mounted door having inturned marginal flanges for closing the lading discharge opening of the hopper, said frame comprising a substantially U-shaped member having a web portion adapted to be secured to the floor of the hopper and upwardly extending leg portions respectively adapted to be secured to the inner and outer sides of the hopper, the leg portion which is adapted to be secured to the outer side of the hopper being inclined outwardly, an upper member connecting the upper ends of said leg portions, a substantially triangular plate having one edge bounding a portion of the lading discharge opening and respectively secured to said inclined leg portion and said upper member, and an angular member surrounding the lading discharge opening, said angular member having a flange riveted to said U-shaped member, to said upper member and to said plate, said angular member also having an outwardly extending flange for cooperating with the inner faces of said marginal flanges of the hinged door to seal the lading discharge opening against the escape of lading.

5. A door frame for the hopper of a railway car provided with a hingedly mounted door having inturned marginal flanges for closing the lading discharge opening of the hopper, a U-shaped member bounding the bottom and two sides of the lading discharge opening, an angular member connecting the upper ends of the portions of the member secured to the inner and outer sides of the hopper, said U-shaped member having flanges whose outer faces are respectively disposed in a common plane, and an angular member surrounding the lading discharge opening having means contacting the outer faces of said flanges and riveted thereto, said angular member also having an outwardly extending flange for cooperating with the inner faces of said marginal flanges of the hinged door to seal the lading discharge opening against the escape of lading.

6. A multipart door frame for the hopper of a railway car provided with a hingedly mounted door having inturned marginal flanges for closing the lading discharge opening of the hopper, said door frame having one part adapted to be secured to the hopper and having portions on all four sides of the lading discharge opening disposed in a common plane, and a second part bounding the lading discharge opening and being provided with angularly disposed flanges, one of the flanges of said second part being riveted to said portions of the first part and another of said flanges extending outwardly from the hopper for cooperating with the marginal flanges of the hinged door to seal the lading discharge opening against the escape of lading.

7. A door frame for the hopper of a railway car provided with a hingedly mounted door having inturned marginal flanges for closing the lading discharge opening of the hopper, said door frame comprising a member of substantially angle shape adapted to be secured to the sides and bottom of the hopper, said member having portions for attachment to the hopper and also having flanges in a common plane parallel with the lading discharge opening, an angular member connecting the free ends of the portions of said member which are adapted to be secured to the sides of the hopper, said angular member also

having a flange disposed in said common plane, and an angle shaped member bounding the lading discharge opening having a flange contacting the flanges of said member and of said upper member and riveted thereto, said angle shaped member having another flange extending outwardly for cooperating with the marginal flanges of the hinged door to seal the lading discharge opening against the escape of lading.

8. A railway car having a hopper provided with a lading discharge opening, said hopper including inner and outer side sheets and a downwardly inclined floor sheet, a center sill having an outwardly projecting flange adjacent its lower edge, said inner side sheet of the hopper being attached to the upper portion of the center sill and being inclined outwardly therefrom to clear the flange thereof and depend therebelow, a door frame secured to said sheets adjacent the lading discharge opening, a downwardly inclined cross ridge sheet having one edge terminating adjacent the top of the door frame and rigidly secured thereto, the inclined portion of said inner side sheet adjacent the door frame being bent outwardly to form a portion closing the upper portion of the hopper disposed in a plane parallel to the adjacent portion of said cross ridge sheet.

9. A railway car having a hopper provided with

a lading discharge opening, said hopper including inner and outer side sheets and a downwardly inclined floor sheet, a center sill having a flange projecting outwardly adjacent its lower edge, the upper edge of the inner side sheet being attached to the center sill and being inclined outwardly and downwardly therefrom to clear the flange thereof and depend therebelow, and a door frame secured to said sheets adjacent the lading discharge opening, the inclined portion of said inner side sheet adjacent the door frame being bent to provide a substantially triangular portion closing the upper portion of said hopper, said triangular portion being inclined upwardly from adjacent said flange of the center sill to the top of said door frame.
